DESIGN FOR A SCALES MODEL ORNAMENT

Jack Galter, Chicago, Ill.

Application December 15, 1939, Serial No. 88,924

Term of patent 7 years

To all whom it may concern:

Be it known that I, Jack Galter, a citizen of the United States of America, residing at 711 West Lake Street, Chicago, Illinois, have invented a new, original, and ornamental Design for a Scales Model Ornament, of which the following is a specification, reference being had to the accompanying drawing, forming a part thereof.

The figure is a perspective view of a scales model ornament, showing my new design.

The essential features of my design reside in the specific base member and standard as shown.

I claim:

The ornamental design for a scales model ornament, substantially as shown and described.

JACK GALTER.
